F. A. STEVENS.
STEAM GENERATOR.

No. 65,295.

Patented May 28, 1867.

*My Francis A. Stevens
for Thomas D. Stetson
Attorney*

United States Patent Office.

FRANCIS A. STEVENS, OF CHICAGO, ILLINOIS.

Letters Patent No. 65,295, dated May 28, 1867; antedated May 22, 1867.

IMPROVEMENT IN STEAM GENERATORS.

The Schedule referred to in these Letters Patent and making part of the same.

TO ALL WHOM IT MAY CONCERN:

Be it known that I, FRANCIS A. STEVENS, of Chicago, in the county of Cook, and State of Illinois, have invented certain new and useful Improvements in Locomotives; and I do hereby declare that the following is a full and exact description thereof.

My improvements relate to a means of promoting the draught and urging the fire.

I will first describe what I consider the best means of carrying out my invention, and will afterwards designate the points which I believe to be new. The accompanying drawings form a part of this specification.

Figure 1 is a cross-section on the line T T in fig. 2.

Figure 2 is a vertical longitudinal section.

Similar letters of reference indicate like parts in all the figures. Tints are employed merely to distinguish parts. The material may be of the ordinary kinds.

A is the barrel of the boiler; A' is the fire-box, and B the internal fire-box or furnace. C is the ash-pan, which may be attached and removed by any of the ordinary approved means. The ash-pan is provided with ordinary dampers in front and rear, operated by suitable connections, to allow of one or both being tightly closed when required. Each side of the ash-pan is provided with openings, in which are inserted short tubes c, open at both ends, to allow air to be received from the exterior. These tubes c may be of uniform diameter, or they may be conical, or of any other form which may be judged most conducive to receive the air with the greatest facility when actuated by the small steam jet discharged into each. D D are horizontal pipes, permanently fitted to the boiler, and receiving steam through the pipes D¹ and D² from the dome at the top of the fire-box, controlled by the cock E. The pipes D D are closed at both ends, and are provided with small orifices, to which may be fitted short nozzles d, adapted to direct a small but powerful current of steam at full-boiler pressure into and along the central line of each of the tubes c, before described, in the ash-pan. The pipes D and their connections may be attached permanently to the boiler, and the nozzles d should be so short as to allow the ash-pan to be raised and lowered in attaching it and disconnecting it without disturbing the steam pipes. The boiler may be of any of the approved styles. So also may the cylinders and all parts of the running-gear. The exhaust steam from both cylinders is delivered through the exhaust pipes G into a capacious chamber, H, mounted in the interior of the smoke pipe I, and arranged therein as represented, so as to leave a space between the two inverted cones, through which the draught may rise and be urged forward by a gentle emission of the exhaust steam from a line of orifices near the base of the chamber H. J represents a cast-iron ring, through which the exhaust steam, at a very moderate pressure, is discharged in a series of streams. This series extends around the base of the chamber H, as represented; and the stream of exhaust steam discharged from each of the orifices of the ring J flows upward in the space between the chamber H and the smoke pipe I, and induces a steady and powerful draught. The chamber H is of such capacity as induces an almost perfect equality in the flow of exhaust steam from the orifices when the engine is working rapidly. The top of the smoke pipe may be provided with any of the strainers, or other approved appliances, in case fuel is burned which produces sparks.

Some of the advantages due to certain features of my invention may be separately enumerated as follows:

1. By the arrangement of the pipes D, with the steam jets d, and their connections relatively to the boiler and ash-pan C, and to the openings c in the ash-pan, I am able to blow the fire with great vigor, by simply shutting the dampers at the front and rear of the ash-pan and opening the cock E; and this whether the engine is running on the track or is standing still, and without interfering with the convenient removal and replacement of the ash-pan as often and as rapidly as may be necessary in any exigency.

2. By the employment of my chamber H and its connections, in combination with my blowing means d c and their connections, I am able, without materially adding to the cost, occupying any considerable space, or cumbering or interfering with any of the ordinary modes of cleaning, adjusting, and repairing the locomotive, to work under all the immense variety of conditions with regard to draught which are required in locomotives, working with almost inappreciable resistance to the exhaust when it alone is employed as the promoter of combustion, and the cock E is shut, because the series of orifices for the jets J may be very capacious without

losing the effect, while, by shutting the damper and opening the cock E to a slight or to its full extent, the vigor of the fire may be increased indefinitely.

3. By elevating my reservoir, H, in the stack, and arranging the ring of jets, J, around the base, as represented, I am able to equalize the flow of the steam, and to make the steam more efficient than usual in promoting the draught without interfering with the free access to the ends of the tubes in the smoke pipes when necessary for repairs, &c.

Having now fully described my invention, what I claim as new therein, and desire to secure by Letters Patent, is as follows:

1. I claim the ash-pan C, having the short tubes e in the sides, arranged as herein specified, relatively to the permanently-fixed pipes D and nozzles d, discharging steam from the boiler into the tubes e, as specified, and allowing the ash-pan to be connected and disconnected without disturbing the steam connection.

2. I claim the steam jets d, blowing into the ash-pan of the locomotive, arranged with reference to the exhaust reservoir H, and the ring of jets J, for facilitating the exit of the gases, substantially as and for the purpose herein specified.

3. I claim the exhaust reservoir H, made to correspond in form with and mounted in the interior of the smoke-stack I, so as to discharge the steam from the ring of jets J, and urge upward the gases in the space between the two conical casings in the stack, in the manner and for the purpose substantially as herein specified.

FRANCIS A. STEVENS.
